UNITED STATES PATENT OFFICE.

DARIO BUCCICONE, OF CANONSBURG, PENNSYLVANIA.

FEEDING MECHANISM FOR TINNING MACHINES.

1,422,535.

Specification of Letters Patent. Patented July 11, 1922.

Application filed May 16, 1921. Serial No. 470,073.

To all whom it may concern:

Be it known that I, DARIO BUCCICONE, a subject of the King of Italy, residing at Canonsburg, in the county of Washington 5 and State of Pennsylvania, have invented certain new and useful Improvements in Feeding Mechanisms for Tinning Machines, of which the following is a specification.

This invention relates to certain new and 10 useful improvements in feeding mechanisms for tinning machines and relates particularly to improved automatic plate or sheet feeding mechanism particularly designed for conveying plates or tins one by one and 15 in rapid succession from a pack or pile to the tinning pot of a tinning machine.

The principal object of the invention is to provide an improved liquid tank adapted to hold the pack of plates and provided with 20 means for elevating the plates one at a time out of the same to an elevated position, the tinning machine being equipped with overhead feeding mechanism to receive the plates thus elevated and deliver the same to 25 the tinning pot, the elevating means and feeding means being adapted for interconnection when the device is in operation and being capable of disconnection for permitting a new filled tank to be brought into 30 place, and the feeding means being extensible and engageable with the elevating means, and means being associated with the extensible feeding means for automatically keeping the elevating means engaged with 35 the plates as they are fed from the tank.

Another object of the invention is to generally improve devices of this character so as to elevate and deliver plates from the tank to the tinning pot in a most expeditious 40 and practical manner and with the necessity of as little attention to the apparatus as possible.

Other objects will become apparent as the nature of the invention is better understood, 45 and the same consists in the novel form, combination and arrangement of parts shown in the accompanying drawings and claimed.

In the accompanying drawings, which 50 illustrate an application of my invention,

Figure 1 is a view partly in longitudinal section and partly in side elevation of an apparatus embodying my invention,

Figure 2 is a view partly in end elevation 55 and partly in transverse section of the apparatus shown in Fig. 1,

Figure 3 is a fragmentary plan view of the feeding and elevating mechanism, partly broken away,

Figure 4 is an elevational view of the 60 extensible frame of the feeding mechanism with the feed roller shafts thereof in section,

Figure 5 is a top plan view thereof,

Figure 6 is a horizontal sectional view 65 of the same taken upon line VI—VI of Fig. 4, and with one of the collars displaced,

Figure 7 is an elevational view of one of the upper members of the extensible frame 70 of the feeding mechanism,

Figure 8 is a fragmentary elevational view of the feeding mechanism collapsed and showing the slidable abutment carriage which engages the elevating means for keeping the latter operatively associated with 75 the plates, parts being removed,

Figure 9 is a view similar to Fig. 8 with the feeding mechanism extended,

Figure 10 is a rear elevational view, partly 80 broken away, of the flux-box and associated parts,

Figure 11 is a top plan view of the device shown in Fig. 10,

Figure 12 is an end elevational view 85 thereof,

Figure 13 is a view similar to Fig. 12 of the opposite end of the flux-box,

Figure 14 is a fragmentary sectional view 90 taken upon line XIV—XIV of Fig. 3, showing the means for preventing more than one plate being elevated at a time by the elevating mechanism,

Figure 15 is a sectional view taken upon line XV—XV of Fig. 14,

Figure 16 is a detail view of the friction 95 pad of the elevating mechanism, and

Figure 17 is a top view thereof.

Referring in detail to the drawings, 5 indicates a liquid containing tank or feed box designed to hold in addition to the liquid, 100 a pack of plates 6, the plates being disposed vertically as shown clearly in Fig. 1, and the tank 5 being preferably of multiple form by being divided into a plurality of chambers through the medium of partitions 105 7, a pack of plates being disposed in each compartment of the tank. As illustrated, the tank 5 is mounted upon a car 8 which is designed to be run into a convenient position for the plates to be reached by the 110 elevated feed mechanism to be presently described.

The flux-box of the tinning machine is indicated at 9, and the metal containing compartment of the tinning pot is designated by the numeral 10, this flux-box being provided with guides 8' between which the plates are to be delivered.

Located over the tank 5 is a feeding mechanism for delivering the plates to the flux-box as they are elevated from the tank. This 10 mechanism and its supporting and driving structure includes a horizontally disposed power shaft 11 having its ends suitably journaled as at 12 at opposite sides of the tank 5 and above the latter.

15 The power shaft 11 is rotatably geared to a vertical shaft 13 as at 11' and the latter is geared to a shaft 14' of the feed rollers 14 of the flux-box which feed the sheets between the guides 8, and rotation may be imparted 20 to said shaft 11 from a suitable motor, not shown. The tinning pot is provided with the usual delivery mechanism including the cooperating friction rolls 17 and 18.

A bracket 19 rests upon each end of the 25 front wall of the tinning machine, and the rear ends of a pair of rods 20 are fixed in each of said brackets, the rods 20 being disposed in a horizontal position slightly below the shaft 11 and being fixed to a suitably supporting block 21 at its other end 30 below the bearing of the shaft 11 in said block as at 12. The block 21 rests on a cleat 21' fixed to a wall of the building. Each bracket 19 has an end portion of a 35 transverse shaft 22 journaled therein, and a plurality of friction wheels 23 are fixed at intervals upon this shaft, while a worm gear 24 is secured upon one end of the latter so as to mesh with the worm portion 25 of the 40 power shaft 11 for causing rotation of this shaft 22 and its friction wheels 23. Another shaft 26 is journaled in vertically adjustable bearings carried by the brackets 19 above the shaft 22, and said shaft 26 is also provided 45 with a plurality of friction wheels 27, each wheel 27 being peripherally engaged with one friction wheel 23 of the shaft 22, and the wheels 23 and 27 being disposed in pairs, one pair for the sheets from each compartment of the tank 5 so that the rollers of the 50 pairs engage the upper and under surfaces of the sheets along the side edges of the latter when said sheets or tins are fed to the flux-box. A shaft hanger 28 is slidably mounted upon each rod 20, and the ends of another transverse shaft 29 are journaled in the lower portions of said shaft hangers 28, while a further transverse shaft 30 is journaled in vertically movable bearings 55 provided in the shaft hangers 28 above the shaft 29. Rollers 31 and 32 similar to the wheels or rollers 23 and 27 and similarly disposed are respectively fixed upon the shafts 29 and 30. A still further shaft hanger 33 is slidably mounted upon each 60

pair of rods 20 adjacent the shaft hanger 28, and this shaft hanger 33 has a pair of superposed shafts respectively indicated at 70 34 and 35 journaled therein similar to the provision of the shafts 29 and 30 in the shaft hanger 28. The shafts 34 and 35 are respectively provided with friction wheels 36 and 37 disposed and related in a manner similar to that described with respect to the wheels 23 and 27. The shafts 22, 29 and 34 are respectively provided with worm gears 15, 38 and 39 meshing with the worm portion 25 of the shaft 11 for driving the rolls or wheels of said shafts 22, 29 and 34. It is to be understood that the rollers 23 and 27, 31 and 32, and 36 and 37 are so related as to permit the passage of the plates therebetween with incident friction sufficient to feed the plates at a uniform speed, which friction may be regulated by the adjustment of the shafts 85 26, 30 and 35 toward or away from the shafts 22, 29 and 34.

Extensible frames or intermediate hangers for the shafts of the feeding mechanism, are provided, and they include lower frames 90 each embodying a pair of slidably connected members or plates 40 and 41 which are provided with longitudinal slots 16 and interengaging collars 42 and 42' respectively integral with the members 40 and 41 and slidable on shafts 22 and 34. As shown in Fig. 4, the shaft 29 passes through the slot of each lower frame, while the shafts 22 and 34 are removably journaled in the ends of the latter. Similarly, each upper frame comprises 100 43 and 44 which are slotted and connected in a similar manner, the shaft 30 being disposed through the slot of each upper frame, and the shafts 26 and 35 being journaled in the 105 members 43 and 44 respectively. The free ends of the plates 43 and 44 of each upper frame are downwardly curved to provide guides 45 and 46 respectively which are adapted to lead the plates from the wheels 110 23 and 27 to the rollers 14 and to lead the plates between the rollers 36 and 37 from the elevating means, which will be presently described, and which is provided in the compartments of the tank 5.

Lazy tongs 47 extend beside the brackets 19 and shaft hangers 28 and 33 and are connected to them so that when the shaft hanger 33 is pulled away from the bracket 19, a similar separating movement between the 120 bracket 19 and the shaft hanger 28 is obtained so as to keep the spaces between these elements as nearly equal as possible, the necessity for which will be apparent.

The movement of the shaft hanger 33 125 away from the bracket 19 is accomplished preferably by means of a weight 48 suspended upon one end of a flexible member 49 which passes around a pulley 50 fixed to the right hand end of one of the rods 20, and 130

which is connected as at 51 to the arm 52 of the shaft hanger 33. A suitable hoisting mechanism generally denoted at 53 may be provided for raising the weight 48 so as to 5 permit retraction of the parts to their normal starting position as shown in Fig. 1, and this movement of the shaft hangers is provided so as to cause the elevating mechanism of each tank compartment to always 10 keep into engagement with the plates 6, said elevating mechanisms each comprising carriages 54 movable transversely of the tank compartment and engageable by a depending abutment or arm 55 for imparting movement to the carriages 54 as allowed by the successive removal of the plates 6 and as influenced by the weight 48 and its connection with the shaft hanger 33. The carriages 54 are mounted for movement transversely of 15 the tank 5, two of said carriages being disposed upon the upper edges of the end walls of said tank, and the others being similarly disposed upon the upper edges of the partitions 7, anti-friction rollers 56 being provided on the carriages for riding upon the upper edges of the end walls and the partitions of the tank 5 so as to insure this movement freely under the action of the weight 48. Each carriage embodies an upper sheet 20 metal frame of substantially C-shape in top plan as seen in Fig. 3 with the ends of the frame disposed in slightly spaced relation to provide a slot 57 through which the edges of the plates 6 move when being elevated 25 and by means of which the said plates are directed between suitable friction rollers 58 and 59 which are respectively secured at intervals upon the transverse shafts 60 and 61 which are journaled in the extensions 52 30 of the shaft hangers 33 forwardly of the shaft 34, said shafts 60 and 61 being arranged in the same horizontal plane and side by side, while the shaft 61 is adjustable to and from the shaft 60 so as to permit obtaining of the proper relation between the 35 friction wheels 58 and 59. These friction wheels 58 and 59 are disposed upon the shafts 60 and 61 in substantially the same relation as hereinbefore described with respect to the friction rollers 23 and 27. 40 Each sheet feeding or elevating mechanism is composed of a pair of carriages 54, and adjacent pairs of said carriages may be integrally formed or rigidly connected as 45 seen in Fig. 2. The pair of carriages for each compartment of the tank 5 supports a depending frame composed of a pair of side plates 62 rigidly connected in spaced relation in any suitable manner and provided 50 with a transverse connecting plate 63 around which a pair of endless chains 64 pass, said chains being arranged, one adjacent each plate 62 and each engaging a sprocket wheel 65 at the lower ends of the plates and a similar sprocket wheel 66 at the upper ends 55 thereof, a shaft being suitably rotatably mounted in the lower ends of the plates 62 and having the sprockets 65 fixed thereon, and a similar shaft being rotatably mounted in the upper members of the carriages 54 60 with the sprockets 66 secured thereon. The chains 64 are connected by a transverse friction member or pad 67 which is disposed so as to engage the outer plates of the piles of plates when said friction members 67 are moved in an orbital path by travelling with the chains 64. 65 The shaft 60 is preferably driven from the shaft 34 by means of a sprocket gearing including a sprocket chain 68, and this rotation of shaft 60 is transmitted to the shaft which carries the sprockets 66 by means of a chain 69 which may be passed around the desired alined ones of the sprocket wheels 70 upon the latter shaft and the sprocket 70 wheels 71 upon the shaft 60. As shown, the sprocket wheels 70 gradually decrease in size from left to right, while the sprocket wheels 71 increase in size in the same direction so that by changing the chain 69 to 80 different pairs of these sprockets, the chain 64 of the sheet elevating means may be driven at different speeds according to the nature of the work. It will be noted that the chain 69 may be removed and when this is done the overhead feeding means may be elevated by reason of the provision of a hinge 50' in the shaft 11 and the break joint 51' in the shaft 13, and the tank 5 may be then taken away so as to bring into place 85 another tank which is filled with plates 6 after the first tank has been emptied. It will also be noted that when the abutment or depending arm 55 engages the adjacent carriage 54, the slots 57 of the carriages are 90 vertically alined with the small spaces between the friction wheels 58 and 59 so as to insure passage of the sheets, without interference, from the elevating means to the overhead feeding means. The connecting 95 plates 63 of the elevating means furnishes a solid backing for the endless members of said elevating means so as to cause firm engagement of the pads 67 with the faces of the outer plates of the piles of plates 6 when the carriages 54 are fed toward said plates 6. 100 From the foregoing, it will be noted that as the piles of plates diminish the carriages 54 move transversely of the tank 5 in a direction away from the tinning pot so that the pads 67 are maintained in contact with the outermost plates and when this takes place the shafts 29 and 34 move relative to the shaft 22 and relative to each other away 105 from the tinning pot and the lazy tongs 47 equalize this relative movement so as to maintain substantially the same space between the shafts 26 and 30 as between the shafts 30 and 35. 110 115 120 125 130

As shown clearly in Fig. 3, the brackets 19 are connected by a transverse bar 75, while the shaft hangers 33 are connected by a similar bar 76 so that rigidity is insured and any movements of these parts must be in unison.

As shown clearly in Figs. 1, 8 and 9, the brackets 19 are provided with bearings 77 and 78 in which shafts 79 are journaled and the latter of which is adjustable toward and from the bearings 77. The shafts 79 are arranged between the shafts 14' and 22 directly above the flux-box 9 and have suitable friction rollers 72 secured thereon in the same relation as has been described with respect to the rollers 27, etc. The shaft in the bearings 77 of the brackets 19 is provided with a sprocket chain connection 80 with the shaft 22 whereby rotation of the friction rollers 72 is had, and intermeshing gears 81 are provided between the shafts in the bearings 77 and 78 and between shafts 22 and 26 as well as between shafts 29 and 30 and 34 and 35 whereby rotation of one of said shafts insures rotation of the other opposed thereto. In other words, each of the shafts 22, 29 and 34 are driven by the power shaft 11 and the rotation thereof is communicated to shafts 26, 30 and 35 by means of spur gear connections 81, while the shaft in the bearings 77 is driven from shaft 22 by the chain gearing 80 and intermeshing spur gears 81 are also provided between the shafts in the bearings 77 and 78 whereby these two latter shafts are also driven in unison.

The collars 42 of the frame members 40, 41, 43 and 44 open into the slots 16 so as to permit insertion of the shafts 22, 26, 34 and 35 concentrically within said collars 42. The collars 42' are then slid and secured within the collars 42 through the use of a set screw or the like whereby said shafts are effectively removably held in operative position. This provides for convenient assembling and disassembling of the parts and also allows rapid repairs. The gear connection between the vertical shaft 13 and one of the shafts 14' of the flux-box preferably comprises a worm gearing as at 82 in Figs. 10 and 11, and, referring to Figs. 16 and 17, it will be seen that the pad 67 of each elevating device is provided with bolts 83 for reception of nuts 84 whereby said pads are fastened to the chains 64.

If desired, suitable brackets 85 may be attached to the flux-box ends so as to permit engagement of hooks therewith whereby the hoisting mechanism 53 may be employed for removing said flux-box for repairs or the like. It is also noted that intermeshing gearing 81 is provided between the shafts 60 and 61 as shown clearly in Fig. 3 for insuring driving of these shafts in unison.

The slots 57 are varied in size for properly

accommodating plates of varying thicknesses while insuring outward passage of only one plate at a time, by means of an adjustable plate 86 for each slot which is suitably mounted for sliding movement in a guide 70 87 and adjustable by a screw 88 as shown in Figs. 14 and 15.

In operation, the tins or plates are passed upwardly from the packs or piles singly and successively to and between the rollers 58 and 59 by means of the elevating devices which include the pads or friction members 67. After a sheet or plate passes the rollers 58 and 59, it is deflected by the guides 46 between the rollers 36 and 37 of the elevated or overhead feeding mechanism to and between the rollers 31 and 32 of the latter and then to and between the rollers 33 and 27 from whence it is deflected downwardly by the guides 45 so as to pass between the rollers 72 and 14 and through the guides 8' in the flux-box.

What is claimed as new is:—

1. The combination with an overhead means for feeding plates to a tinning pot, means for elevating plates one by one from a substantially vertical stack to said overhead feeding means and including a movable friction member engaging the outermost plate of the pile and movable transversely of the latter for 95 maintaining frictional engagement with said outermost plate, said overhead feeding means being extensible in a direction transversely of the pile of plates and engaging the plate elevating means so as to move it 100 transversely of the pile of plates when said overhead feeding means is extended, means to normally extend said overhead feeding means, driving means for said overhead feeding means, and detachable operating 105 connections between the overhead feeding means and the plate elevated means, said feeding means and elevating means being devoid of interconnections with the exception of said operating connections, and a 110 portable carrier for the pile of plates upon which said elevating means is mounted.

2. The combination with an extensible overhead feeding means for moving plates to a tinning pot, means to normally extend 115 said feeding means, means to elevate plates one by one from a pile to said feeding means, means carried by the feeding means and engageable with the elevating means to maintain the latter engaged with the outermost plate of the pile as said feeding means is extended, a liquid tank in which said plates are piled, said elevating means including friction members supported from a carriage movable transversely of the tank, and driving mechanism for moving the friction members in an orbital path, said driving mechanism comprising detachable gearing between the elevating means and the feeding means.

3. The combination with an extensible overhead feeding means for moving plates to a tinning pot, means to normally extend said feeding means, means to elevate plates one by one from a pile to said feeding means, means carried by the feeding means and engageable with the elevating means to maintain the latter engaged with the outermost plate of the pile as said feeding means is extended, a liquid tank in which said plates are piled, said elevating means including friction members supported from a carriage movable transversely of the tank, and driving mechanism for moving the friction members in an orbital path, said driving mechanism comprising detachable gearing between the elevating means and the feeding means, said detachable gearing comprising a chain speed gearing.

4. The combination with an extensible overhead feeding means for moving plates to a tinning pot, means to normally extend said feeding means, means to elevate plates one by one from a pile to said feeding means, means carried by the feeding means and engageable with the elevating means to maintain the latter engaged with the outermost plate of the pile as said feeding means is extended, said extensible feeding means including a plurality of sets of friction feed rollers arranged in spaced relation, one set of said rollers being relatively fixed, and the remaining sets of rollers being movable horizontally toward and away from each other as well as away from said one set.

5. The combination with an extensible overhead feeding means for moving plates to a tinning pot, means to normally extend said feeding means, means to elevate plates one by one from a pile to said feeding means, means carried by the feeding means and engageable with the elevating means to maintain the latter engaged with the outermost plate of the pile as said feeding means is extended, said extensible feeding means including a plurality of sets of friction feed rollers arranged in spaced relation, one set of said rollers being relatively fixed, and the remaining sets of rollers being movable horizontally toward and away from each other as well as away from said one set, and means to equalize the spaces between said sets of rollers as the feeding means is extended, said extensible feeding means including a plurality of sets of friction feed rollers arranged in spaced relation, one set of said rollers being relatively fixed, and the remaining sets of rollers being movable horizontally toward and away from each other as well as away from said one set, and means to equalize the spaces between said sets of rollers as the feeding means is extended, said last named means comprising lazy tongs connected with the sets of rollers.

6. The combination with an extensible overhead feeding means for moving plates to a tinning pot, means to normally extend said feeding means, means to elevate plates one by one from a pile to said feeding means, means carried by the feeding means and engageable with the elevating means to maintain the latter engaged with the outermost plate of the pile as said feeding means is extended, said extensible feeding means including a plurality of sets of friction feed rollers arranged in spaced relation, one set of said rollers being relatively fixed, and the remaining sets of rollers being movable horizontally toward and away from each other as well as away from said one set, and means to equalize the spaces between said sets of rollers as the feeding means is extended, said extensible feeding means including a plurality of sets of friction feed rollers arranged in spaced relation, one set of said rollers being relatively fixed, and the remaining sets of rollers being movable horizontally toward and away from each other as well as away from said one set, and means to equalize the spaces between said sets of rollers as the feeding means is extended, said last named means comprising lazy tongs connected with the sets of rollers.

7. The combination with an extensible overhead feeding means for moving plates to a tinning pot, means to normally extend said feeding means, means to elevate plates one by one from a pile to said feeding means, means carried by the feeding means and engageable with the elevating means to maintain the latter engaged with the outermost plate of the pile as said feeding means is extended, said extensible feeding means including a plurality of sets of friction feed rollers arranged in spaced relation, one set of said rollers being relatively fixed, and the remaining sets of rollers being movable horizontally toward and away from each other as well as away from said one set, and means to equalize the spaces between said sets of rollers as the feeding means is extended, said last named means comprising lazy tongs connected with the sets of rollers.

8. The combination with an extensible overhead feeding means for moving plates to a tinning pot, means to normally extend said feeding means, means to elevate plates one by one from a pile to said feeding means, and means carried by the feeding means and engageable with the elevating means to maintain the latter engaged with the outermost plate of the pile as said feeding means is extended, said feeding means comprising extensible frames with spaced sets of friction rolls between which the plates are adapted to pass and by means of which they are fed to the tinning pot, certain of said frames being provided with downwardly curved end members to guide the plates from the elevating means between said friction rollers and from said friction rollers to the tinning pot.

9. The combination with an extensible overhead feeding means for moving plates to a tinning pot, means to normally extend said feeding means, means to elevate plates one by one from a pile to said feeding means, means carried by the feeding means and engageable with the elevating means to maintain the latter engaged with the outermost plate of the pile as said feeding means is extended, said extensible feeding means including a plurality of sets of friction feed rollers arranged in spaced relation, one set of said rollers being relatively fixed, and the remaining sets of rollers being movable horizontally toward and away from each other as well as away from said one set, and means to equalize the spaces between said sets of rollers as the feeding means is extended, said last named means comprising lazy tongs connected with the sets of rollers.

with the outermost plate of the pile as said feeding means is extended, said feeding means comprising extensible frames with spaced sets of friction rolls between 5 which the plates are adapted to pass and by means of which they are fed to the tinning pot, certain of said frames being provided with downwardly curved end members to guide the plates from the elevating means 10 between said friction rollers and from said friction rollers to the tinning pot, a plurality of transverse shafts upon which said friction rollers are mounted, spaced shaft hangers slidably mounted above the tank 15 for movement transversely of the latter and in which said shafts are journaled, an outward horizontal extension upon the outermost one of said shaft hangers, a pair of transverse shafts arranged in the same horizontal plane and journaled in the extension 20 of said shaft hanger, a plurality of friction rollers mounted upon said last named shafts arranged to have the plates passed therebetween from the elevating means to 25 said guide members at one end of the feeding means, and means exerting a pull upon said extension to extend the feeding means.

10. The combination with an overhead means for feeding plates to a tinning pot 30 including spaced sets of feed rollers movable relative to each other so as to vary the distance between the same, means to elevate plates one by one from a pile to said overhead feeding means movably 35 mounted for movement toward the plates, means to normally move said sets of rollers relative to each other, and means operatively connecting the overhead feeding means with the elevating means for causing 40 movement of the elevating means when the sets of rollers of the feeding means are relatively moved so as to maintain operative engagement of the elevating means with the outermost plate of the pile of 45 plates as the latter are fed from the pile.

11. In a tinning machine feeding apparatus, a receptacle with plates vertically disposed in a pile or pack, a movable carriage supported by the receptacle and having depending friction means for elevating plates one by one from said pile, an extensible overhead feeding means to receive plates from the elevating means and deliver them to a tinning pot, said feeding means comprising 55 a plurality of sets of friction rollers, a drive shaft rigidly mounted beside the feed rollers transversely of the plates, drive connections between said shaft and each set of rollers, and drive connections between one set of 60 rollers and said elevating means.

12. In a tinning machine feeding apparatus, a receptacle with plates vertically disposed in a pile or pack, a movable carriage supported by the receptacle and having depending friction means for elevating plates one by one from said pile, an extensible overhead feeding means to receive plates from the elevating means and deliver them to a tinning pot, said feeding means comprising a plurality of sets of friction rollers, a drive shaft rigidly mounted beside the feed rollers transversely of the plates, drive connections between said shaft and each set of rollers, drive connections between one set of rollers and said elevating means, and a rod rigidly mounted beneath the drive shaft, said feeding means further including shaft hangers slidably mounted upon said rod. 75

13. The combination with an extensible overhead means to feed plates to a tinning pot, means to elevate plates one by one from a pile to said feeding means and movable relative to the plates so as to be capable of maintaining operative engagement with the latter, means to normally extend said feeding means, and means operatively associating the feeding means with the elevating means whereby registry is maintained between the latter as the feeding means is extended, said last named means also causing movement of the elevating means as the feeding means is extended for maintaining operative engagement of the elevating means with the plates. 80

14. The combination with an extensible overhead feeding means for moving plates to a tinning pot, means to normally extend said feeding means, means to elevate plates one by one from a pile to said feeding means, means carried by the feeding means and engageable with the elevating means to maintain the latter engaged with the outermost plate of the pile as said feeding means is extended, a liquid tank in which said plates are piled, said elevating means including friction members supported from a carriage movable transversely of the tank, driving mechanism for moving the friction members in an orbital path, said driving mechanism comprising detachable gearing between the elevating means and the feeding means, said extensible overhead feeding means being mounted for upward swinging movement away from the elevating means when said detachable gearing is detached, and means to upwardly swing said overhead feeding means. 95

In testimony whereof I affix my signature.

DARIO BUCCICONE.
